(57) **CLAIM**

The ornamental design for an adjustable dog collar, as shown and described.

DESCRIPTION

FIG. 1 is a first perspective view of an adjustable dog collar showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an exploded view of the adjustable dog collar thereof; and,

FIG. 10 is an enlarged view of the selected portion 10 in FIG. 1.

The dash-dash broken lines in the drawings depict portions of the adjustable dog collar that form no part of the claimed design. The dot-dash broken lines represent boundaries of the enlarged portions and form no part of the claimed design.

1 Claim, 10 Drawing Sheets
